UNITED STATES PATENT OFFICE

JOHN F. O'CONNOR, OF CHICAGO, ILLINOIS, ASSIGNOR TO W. H. MINER, INC., OF CHICAGO,
ILLINOIS, A CORPORATION OF DELAWARE

HAND BRAKE

Application filed July 14, 1930. Serial No. 467,824.

This invention relates to improvements in hand brakes. One object of the invention is to provide a hand brake mechanism especially adapted for railway cars, including chain winding means and worm gearing for actuating the same, wherein the wear is greatly reduced by distributing the load through the use of a pair of chain winding drums both operated by a single worm element meshing with a pair of worm gears connected to the drums, and wherein means is provided for disconnecting the worm gears from the drums to permit free running of the latter to quickly release the brakes.

Another object of the invention is to provide in a brake mechanism of the character indicated in the preceding paragraph, releasable clutch means between the worm gearing and each chain winding drum to permit free running of the latter in release, wherein the clutch means is operated by a single manually controlled actuating member.

Other objects of the invention will more clearly appear from the description and claims hereinafter following.

In the drawings, forming a part of this specification, Figure 1 is a vertical sectional view through my improved hand brake mechanism, illustrating the same applied to the end wall of a railway car, the section being in a plane parallel to said end wall. Figures 2, 3 and 4 are vertical, transverse sectional views corresponding respectively to the lines 2-2, 3-3 and 4-4 of Figure 1. And Figure 5 is a view similar to Figure 1, partly broken away, illustrating another embodiment of the invention.

Referring first to the embodiment of the invention, illustrated in Figures 1 to 4 inclusive, my improved hand brake mechanism proper is mounted within a housing 10, which is fixed to the vertical end wall of the car, indicated by 11. The housing comprises spaced vertical side walls 12 and 13, a front wall 14, a rear wall 15 and curved top and bottom walls 16-16. The bottom wall 16 of the housing is open at the center, as indicated at 17, to accommodate the brake chain which is connected to the brake mechanism proper

of the car in the usual manner. As most clearly shown in Figure 2, the upper part of the housing 10 is offset outwardly with respect to the lower portion thereof, that is the entire housing is outwardly inclined with respect to the end wall 11 of the car. The housing may be secured to the end wall 11 in any suitable manner, and as herein shown is provided with laterally projecting securing flanges 18-18 at opposite sides thereof, which are riveted to the end wall 11 of the car.

My improved hand brake mechanism proper, which is mounted within the housing, comprises broadly a worm element A, a hand wheel B; two worm gears C-C; two chain winding drums D-D; a pair of springs F-F for urging the drums toward the gears; a clutch releasing means including a slide G, an actuating lever H and a connecting link K.

The worm element A is in the form of an elongated sleeve-like member threaded at the inner end, as indicated at 19. The worm member is supported for rotation within the housing by means of a rod or bolt 20 extending through said member and having the headed end 21 thereof seated in a pocket 22 provided in the rear wall of the housing. As shown most clearly in Figure 2, the rear wall of the housing is thickened at the point where the head is anchored to strengthen that portion of the wall. At the forward end, the worm member A is directly supported for rotation in the front wall of the housing, the worm member being provided with a cylindrical bearing portion 23 at said end rotatable in a bearing opening 24 in the front wall 14 of the housing. The housing wall adjacent the bearing portion referred to is thickened, as shown, so as to strengthen the same. At the outer end the worm element A is provided with a laterally projecting annular flange or rib 25, which serves to retain the hand wheel B on the worm element. The hand wheel B is provided with an opening 26 receiving the outer end portion of the worm element, said opening 26 being enlarged at the outer end to provide a retaining shoulder 27 cooperating with the retaining rib or flange 25. At the outer end, the rod or bolt 20 is provided with a retaining nut 28 which

8

locks the rod to the worm element, the nut being seated in a pocket provided in the outer end of said worm element. A spacing washer or shim 29 is preferably interposed between the inner end of the worm element and the inner face of the rear wall of the housing.

The two worm gears C—C are of similar design, each being provided with threads or teeth meshing with the threads of the worm element A. The chain winding drums D—D are also of similar design, each being in the form of a spool element having an annular flange 30 at the outer end thereof. Both the worm wheels C—C and the chain winding drums D—D are supported within the housing in a similar manner, each being mounted on a supporting shaft 31 anchored in the opposite side walls of the housing. Each shaft 31 is provided with an enlarged, central, substantially cylindrical portion 32 on which the corresponding drum D is rotatable. Rearwardly of the cylindrical portion 32, the shaft 31 is reduced in diameter, as indicated at 33, and the corresponding worm wheel C is rotatably supported on said portion 33. The rear extremity of each shaft 31 is still further reduced and is supported within an inwardly projecting boss 34 provided on the rear wall of the housing, the shaft being secured in position by means of a nut 35 threaded on the inner end thereof and seated within a pocket 36 provided in the rear wall of the housing. At the forward end, each shaft 31 is of smaller diameter than the cylindrical central portion 32 thereof, said reduced portion being designated by 37. A shoulder is thus provided at the outer end of the section 32 of each shaft. The forward extremity of the section 37 of each shaft is also threaded and receives a nut member 38. A thimble or sleeve 39 is slidably mounted on the reduced section 37 of each shaft, the thimble having an annular flange 40 at the inner end thereof which normally bears on the shoulder at the outer end of the section 32. A collar 41 is interposed between the nut 38 at the outer end of each shaft and the sleeve or thimble 39, the outer end of the sleeve or thimble being spaced from the collar 41 so as to permit reciprocating movement of the thimble. The collars 41 are accommodated within openings 42 provided in the side wall 12 of the housing. The springs F—F, which are two in number, are mounted on the thimbles 39, being interposed between the flanges thereof and the collars 41, thus yieldingly holding the thimbles engaged with the shoulders of the shafts 31. At the inner end, each chain winding drum D is provided with a plurality of clutch teeth 43, which cooperate with clutch teeth 44 provided in a pocket 45 at the corresponding side of the cooperating worm wheel C. As will be evident upon reference to Figure 1, the cooperating clutch teeth of the top and bot-

tom chain winding drums and top and bottom worm wheels are reversely arranged, inasmuch as the two chain winding drums rotate in opposite directions when the chain is being wound thereon. Each chain winding drum is provided with an outstanding lug 46 to which the end of a chain member 47, shown in dotted lines in Figure 4, is secured. The chain member 47 is trained over a sheave or pulley 48, as clearly shown in Figure 4, which pulley is connected to a rod 49 directly connected with the chain, which leads to the brake mechanism proper of the car, not shown.

As most clearly illustrated in Figure 1, each of the worm wheels is provided with a bearing opening 50 at the right hand side thereof, as viewed in Figure 1, receiving the corresponding bearing boss 34 of the wall 13 of the housing.

The clutch releasing means comprising the elements G, H and K is employed to retract the chain winding drum so as to disengage the clutch means thereof from the clutch means of the two worm wheels. The lever H is pivotally supported on a pivot pin or bar 51 secured in the front and rear walls of the housing. At the bottom end, the lever H is provided with a hand grip by which the same may be manipulated. The upper end of the lever above the pivot 51 thereof is connected to the slide G by means of the link K, which has the outer end thereof pivoted to the inner end of the lever H and the inner end thereof pivoted to a pair of outstanding lugs 52—52 on the slide G. The slide G is provided with top and bottom openings 53—53 through which the spool portions of the chain winding drums D—D extend. A shim or washer 54 is interposed between the annular flange 30 of each drum and the outer face of the slide G. In order to minimize wear between the outer ends of the chain winding drum and the thimbles 39, each drum is provided with a wear plate or shim 55 seated in a pocket at the outer end of said drum. As most clearly shown in Figure 1, the parts are so proportioned that the inner ends of the thimbles 39 are normally slightly spaced from the outer ends of the drums when the latter are in clutching engagement with the worm wheels, thereby eliminating friction and reducing the wear between these parts.

In assembling my improved hand brake mechanism, the upper chain winding drum D, and the cooperating worm wheel, together with the slide G and the actuating means therefor, are first inserted within the housing. The worm member or element A may then be placed in position and the bottom drum and worm wheel entered within the housing. The parts are then secured in assembled relation by the shafts 31—31 and the rod 20. The rod 20 is entered through the rear wall of the housing, thus securing the worm element A

in position. Each shaft 31 is applied in the following manner: Before entering the shaft within the housing, the thimble and spring F are assembled therewith and the collar 41 placed thereon, the same being secured in position by the nut 38. The shaft 31 with the parts thus assembled therewith is then entered through the opening 42 in the front wall of the housing, the section 32 of the shaft being passed into the corresponding drum D and the rear end of the shaft engaged within the corresponding worm wheel C. The rear end of the shaft is then secured within the opening of the rear wall of the housing.

The operation of my improved hand brake mechanism, as illustrated in Figures 1 to 4 inclusive, is as follows, during application of the brakes: The operating hand wheel B is rotated in a clockwise direction, as viewed in Figure 1, thereby rotating the worm element A in a corresponding direction. The two worm gears which are meshed with the worm element are rotated in reverse directions, the upper worm wheel being rotated in a counter-clockwise direction, as viewed in Figure 2, and the lower worm wheel being rotated in a clockwise direction, as viewed in said figure. Inasmuch as the two chain winding drums D—D are at this time in clutching engagement with the worm wheels, they will be rotated in corresponding directions and the chain member 47 wound thereon, thus tightening the brake chain which is connected to the member 49. During the entire chain winding operation the clutch elements of the drums and worm wheels will be maintained in clutching engagement by the spring F—F. When it is desired to quickly release the brakes, the lever H is pulled in a righthand direction, as viewed in Figure 1, thereby pulling the slide G to the left, as viewed in said figure, carrying the chain winding drums D—D therewith and disengaging the clutch elements thereof from the cooperating clutch elements of the worm wheels. When the parts have been completely disengaged, free rotation of the two chain winding drums is permitted, thereby quickly releasing the brakes.

Due to the spring action of the spring members F—F, the chain winding drums D—D will be urged toward the worm wheels C—C and the clutch teeth of these members will be re-engaged as soon as the brakes are completely released and the chain winding drums become substantially stationary. In case of the teeth of the clutch members not registering exactly, a slight rotation of the worm wheels at the beginning of the chain tightening operation will bring the same into registration and full clutching engagement.

In case it is found desirable or necessary to back off or ease off the brakes, the hand wheel is rotated in a contra-clockwise direction, as viewed in Figure 1, thus rotating the chain winding drums in unwinding direction

through the connecting worm gear means, the drums at this time being in clutching engagement with the worm wheel members.

Referring next to the embodiment of the invention illustrated in Figure 5, the general construction is broadly the same as that of the mechanism hereinbefore described and illustrated in Figures 1 to 4 inclusive, the clutch shifting means only being modified. The hand brake mechanism, as illustrated in Figure 5, includes a housing 110 in which the operative parts of the brake mechanism are enclosed. The chain winding drum members, which are indicated by D'—D' are in the form of spools having annular flanges 130—130 at the outer ends thereof. The winding drums D'—D' are driven by worm wheels, a worm element and a hand wheel connected to the worm element of exactly the same construction as the corresponding members C—C, A and B hereinbefore described. The chain winding drums D'—D' and the cooperating worm wheels are also provided with inter-engaging clutching teeth. The chain winding drums and the worm wheels are mounted on cylindrical shafts 131—131 which are anchored in opposed walls of the housing. The shafts 131—131 are preferably of uniform diameter throughout the major portion thereof and are provided with oil feeding ducts 160—160, as shown in dotted lines in Figure 5.

The means for reciprocating the chain winding drums D—D to engage the clutch teeth thereof with the worm wheels and disengage the same comprises yoke means in the form of a pair of plates M and N. The plate M is provided with a pair of upstanding spaced ears disposed at opposite sides of the same, the ears extending outwardly of the plate N and being pivoted to the inner end of an operating lever P by means of a pivot member 161. The operating lever P is pivoted at 162, the pin 162 being secured in the opposite walls of the housing. The plate M is provided with a pair of openings 163—163 at opposite ends thereof, which receive the spool portions of the chain winding drums D'—D', the openings being preferably formed by fork sections at the ends of the plate. The plate N, which is disposed on the outer sides of the flanges 130—130 of the two drums, is provided with openings 164 at opposite ends thereof, through which the shafts 131—131 extend, the shafts forming guide means for said plate. At the center, on the outer side thereof, the plate N has a projecting journal member 165 engaging the pin 161 at the inner end of the operating lever P. The opening in the bearing projection 165 is preferably in the form of an outwardly opening slot, as clearly shown in Figure 5.

The operation of the brake mechanism illustrated in Figure 5 is substantially the same

as the operation of the mechanism hereinbefore described, the two chain winding drums being rotated in reverse directions during the chain tightening operation 5 by rotation of the worm element which meshes with the two worm gears. During the chain tightening operation, the chain winding drums D'-D' are maintained in clutching engagement with the cooperating worm 10 wheels by the yoke means, the latter being urged to the right, as viewed in Figure 5, through the action of gravity on the operating lever P. As will be evident, backing up or easing up of the brakes is effected by rotating the operating hand wheel in a reverse 15 direction to the rotation thereof during the tightening of the chain.

In order to quickly release the brakes, the hand grip portion of the operating lever P is pulled upwardly and to the right, as viewed in Figure 5, thereby pulling the yoke means, including the plate M, outwardly, carrying the drums D'-D' therewith through engagement of the plate M with the 25 flanges 130-130. In re-engaging the chain winding drums D'-D' with the worm wheels, the drums are forced to the right, as viewed in Figure 5, by means of the plate N, which is pushed inwardly through operation 30 of the lever P by engagement of the pin 161 thereof with the bearing projection 165. As will be evident, the lever P will be urged to the left by the action of gravity, thereby forcing the plate N to the right. Although 35 the lever P is normally returned to the original position by the action of gravity, it will be clear that the same may be manually manipulated to effect restoration of the chain winding drums D'-D' to clutching position 40 with the worm wheels.

I have herein shown and described what I now consider the preferred manner of carrying out my invention, but the same is merely illustrative and I contemplate all changes 45 and modifications that come within the scope of the claims appended hereto.

I claim:

1. In a hand brake mechanism, the combination with a rotatable worm element; of 50 means for rotating said element; a pair of chain winding drums disposed at diametrically opposite sides of said worm element; a worm wheel rotatable with each drum for driving the same, said worm wheels being 55 rotatable about parallel axes disposed transversely of the axis of the worm element and in a common plane inclined to the axis of rotation of the worm element.

2. In a hand brake mechanism, the combination with a worm member rotatable 60 about a horizontal axis; of means for rotating said worm member; a pair of worm wheels disposed respectively above and below said worm element and meshing therewith, said worm wheels being rotatable about

horizontal axes transverse to the axis of rotation of the worm element, said axes of rotation of said worm wheels being offset laterally with respect to each other; and a pair of chain winding drums having driving connections with said worm wheels. 70

3. In a hand brake mechanism, the combination with a pair of chain winding drums; of a pair of worm wheels for actuating said drums; manually actuated means 75 for simultaneously establishing driving relation between said worm wheels and drums; a worm element for actuating said worm wheels; and means for rotating said worm element.

4. In a hand brake mechanism, the combination with a pair of chain winding drums; of a worm wheel for each drum; cooperating clutch means on said drums and worm wheels; means for reciprocating said drums 85 and worm wheels with respect to each other to engage and disengage the clutch means thereof; and a rotatable worm element cooperating with both worm wheels for actuating the same. 80

5. In a hand brake mechanism, the combination with a pair of chain winding drums; of a worm wheel for each drum; cooperating clutch means on each drum and 90 cooperating worm wheel; a rotatable worm element for actuating both of said worm wheels; and means for reciprocating said drums to engage the clutch means thereof with the clutch means of the worm wheels and also to disengage said clutch means. 95

6. In a hand brake mechanism, the combination with a pair of worm wheels; of a pair of chain winding drums cooperating with said worm wheels, said drums being reciprocable toward and away from said worm 105 wheels; cooperating clutch means on said drums and worm wheels; spring means for urging said drums toward the worm wheels; lever-actuated clutch disengaging means for retracting said drums to disengage the same 110 from the worm wheels; and a worm element for actuating said worm wheels.

7. In a hand brake mechanism, the combination with a worm wheel; of a chain winding drum cooperating with said worm wheel, 115 said drum and wheel being reciprocable toward and away from each other; cooperating fixed clutch projections on said drum and wheel respectively; spring means for holding said drum yieldingly engaged with the clutch projections of the worm wheel; lever-actuated clutch disengaging means for retracting said drum and disengaging the same 120 from the clutch projections of the worm wheel; and a worm element for actuating said worm wheel. 125

8. In a hand brake mechanism, the combination with a worm element; of a pair of worm wheels driven by said worm element; a pair of chain winding drums, each of said 130

drums and the corresponding worm wheel having cooperating clutch means thereon, said drums being reciprocable with respect to the worm wheels to engage and disengage the clutch means thereof; and means for reciprocating said drums including lever operated yoke means having shouldered engagement with said drums.

9. In a hand brake mechanism, the combination with a rotary worm element; of a pair of worm wheels meshing with said element, each of said wheels having clutch means thereon; a pair of rotary chain winding drums, each having clutch means thereon cooperating with the clutch means of one of said wheels, said drums being reciprocable toward and away from said wheels to engage and disengage the clutch means thereof, each of said drums having an annular flange thereon; and means for reciprocating said drums including yoke elements embracing said annular flanges, and a lever for actuating said yoke elements.

In witness that I claim the foregoing I
25 have hereunto subscribed my name this 10th
day of July, 1930.

JOHN F. O'CONNOR.
